UNITED STATES PATENT OFFICE.

ERNEST H. WOELFFEL, OF POINT PLEASANT, WEST VIRGINIA; ASSIGNOR TO WEST VIRGINIA MALLEABLE IRON CO., OF POINT PLEASANT, WEST VIRGINIA.

CORNER-POST FASTENER.

1,074,919.

Specification of Letters Patent.

Patented Oct. 7, 1913.

Application filed January 27, 1913. Serial No. 744,468.

To all whom it may concern:

Be it known that I, ERNEST H. WOELFFEL, a citizen of the United States, residing at Point Pleasant, in the county of Mason and State of West Virginia, have invented a new and useful Corner-Post Fastener, of which the following is a specification.

My invention relates to new and useful improvements in corner post fasteners for beds.

The object of the invention is the provision of a device of this character which can be used with the three piece form of bed in which the springs and side rails form one member, or the old form of bed in which the springs are made separate from the side rails.

With these and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings:—Figure 1 is a perspective showing my device attached to three piece form. Fig. 2 is a sectional view of the three piece form. Fig. 3 is a detail of the hook for the three piece form. Fig. 4 is a perspective showing the form for separate side rails. Fig. 5 is a detail showing the hook member inverted. Fig. 6 is a modified form of socket.

In the manufacture of iron beds there is that form known as the three piece bed, comprising the head and foot sections and the spring section which includes the side rails and that form in which the side rails are made a separate part from the spring member.

My invention is particularly adapted for either form of bed and in Figs. 1, 2 and 3 of the drawings I have illustrated the form of my invention used on the three piece form of bed and in Figs. 4 and 5 have shown that form used on the bed in which the side rails and springs are formed separately.

In describing the invention I will first refer to the form of the invention illustrated in Figs. 1, 2 and 3 and the numeral 1 indicates the bed post of ordinary construction to which is secured the socket

member 2 having the tapered interior surfaces indicated by 3. The socket member is secured to the post by means of the bolt 4 and nut 5. It will be noted that by having the interior of the socket tapered from either end that the socket may be reversed at any time.

The numeral 6 represents a socket member adapted to receive the side rails 7 of the spring section and formed integral with the socket member is the forked hook 8 and the upward extension 9 to which may be secured the cross rail 10 of the spring frame. As will be noted the hook member 8 is tapered to fit the socket. A spacing bar 11 is provided for properly spacing the socket members.

As clearly shown in Fig. 1 of the drawing the socket is made of greater width than the hook member so as to leave the space 12 indicated at 12. This will allow for a certain amount of lee-way in the adjustment of the socket members and side rails. As will be noted the forked hook member straddles the bolt 4 which passes through the socket member. Strengthening ribs 13 are provided extending from the hook member 8 to the upward extension 9.

In Figs. 4 and 5 which represent my invention as applied to that form of bed using the separate side rails the numeral 14 represents the post and 15 the socket members secured thereto by means of the bolts as described for Figs. 1 and 2. In this form of the invention I provide the angle iron socket member 16 provided with the flanges 17 adapted to receive the side rails 18. Formed integral with this socket member is the tapered hook member 19 which is adapted to enter the socket and straddle the bolt members as described in Figs. 1 and 2. In this form of my invention as in the previously described form the socket is of greater width than the hook member so as to allow for any irregularities in the adjustment of the several parts.

In Fig. 6 I have illustrated a modified form of the socket member which may be used with either form of my invention and as will be noted this consists of the socket member 20 provided with the integral extension 21 to which the head or foot rail 22 may be secured.

From the above description it will be noted that I have provided a simple form

of corner fastener which can be used with either form of bed and by having the socket member of greater width than the hook member and having the hook member tapered, the hook member will adjust itself in the socket member.

Having fully described my invention which I claim and desire to secure by Letters Patent is:—

- 10 1. A device of the class described, comprising a reversible socket member secured to a post by a bolt passing through the post and socket member, and a tapered forked hook member adapted to straddle the bolt, said hook member having an integral socket for receiving the end of a side rail, and an upwardly extending extension for receiving an end rail.

2. A device of the class described comprising a reversible tapered socket member secured to the post, and a tapered hook member adapted to enter the socket, a socket formed integral with the hook member for receiving a side bar, an upwardly extending member formed integral with the hook, and an angle iron end rail secured to the upwardly extending member for receiving the ends of the springs.

In testimony that I claim the foregoing as my own, I have hereto affixed my signature in the presence of two witnesses.

ERNEST H. WOELFFEL.
